US00D881916S

(12) **United States Design Patent** (10) **Patent No.:** **US D881,916 S**
Mead et al. (45) **Date of Patent:** **** Apr. 21, 2020**

(54) **DISPLAY SCREEN WITH GRAPHICAL USER INTERFACE FOR FLUID MIXING**

(71) **Applicant: LIFE TECHNOLOGIES CORPORATION**, Carlsbad, CA (US)

(72) **Inventors:** **Joshua Mead**, San Diego, CA (US); **Scott Rickes**, San Diego, CA (US); **Sean Zimmerman**, Encinitas, CA (US); **Alessandra Barbosa**, San Diego, CA (US); **Mio Ling**, Singapore (SG); **Woon Liang Soh**, Singapore (SG); **Kevin Mullen**, Smithfield, UT (US); **Christopher Brau**, Grand Island, NY (US); **Jordan Cobia**, Wellsville, UT (US); **Harmon Cosme Sicut, Jr.**, Singapore (SG)

(73) **Assignees:** **Life Technologies Corporation**, Carlsbad, CA (US); **Life Technologies Holdings PTE Limited**, Singapore (SG)

(**) **Term:** **15 Years**

(21) **Appl. No.:** **29/649,421**

(22) **Filed:** **May 30, 2018**

(51) **LOC (12) Cl.** **14-04**

(52) **U.S. Cl.**

USPC **D14/486**

(57) **CLAIM**

The ornamental design for a display screen with graphical user interface for fluid mixing, as shown and described.

DESCRIPTION

The sole FIGURE is a front view of a display screen with graphical user interface for fluid mixing for our new design. The broken line showing of a display screen with graphical user interface is included for the purpose of illustrating portions of the article and forms no part of the claimed design.

1 Claim, 1 Drawing Sheet
